UNITED STATES PATENT OFFICE.

ROBERT P. KING, OF GREENSBORO, NORTH CAROLINA.

DESIGN FOR A WALL CABINET.

Application filed April 14, 1925. Serial No. 13,181. Term of patent 14 years.

To all whom it may concern:

Be it known that I, ROBERT P. KING, a citizen of the United States, residing at Greensboro, in the county of Guilford and State of North Carolina, have invented a new, original, and ornamental Design for Wall Cabinet, of which the following is a specification.

Reference being had to the accompanying drawing, in which—

The single figure represents a perspective view of the wall cabinet, showing my new design.

I claim:

The new, original and ornamental design for a wall cabinet, substantially as shown.

In testimony, that I claim the foregoing as my own, I have hereto affixed my signature.

ROBERT P. KING.
